CARD SORTING MACHINE

Blake L. Mishey, Lyndhurst, Ohio

Application November 19, 1949, Serial No. 128,465

8 Claims. (Cl. 214—11)

1

This invention relates to sorting machines and more particularly to a new and improved machine for sorting material of a flexible nature such as checks, cards, coupons, sales slips, tickets and other like items and for the purpose of this description such items are hereinafter referred to as "cards."

It is among the objects of the present invention to provide a new and improved sorting machine wherein a stack of cards to be sorted are positioned in a container and mechanically picked up individually and deposited in receiving receptacles in accordance with nomenclature appearing thereon, which may be alphabetical or numerical, without the necessity of manually handling the cards or providing the same with special sorting provisions such as punchings, cutouts, and the like.

A further object of the invention is to provide in a sorting machine new and improved means for mechanically picking up the top card from a stack and depositing it upon a conveyor for transmission to a predetermined designated receptacle.

A still further object of the invention is to provide in a sorting machine means for coordinating the pick up mechanism and transmission mechanism to effect a more rapid sorting of the cards.

A still further object of the invention is to provide a sorting machine for cards made of a flexible material which is simple to manufacture, positive in operation, economical to use and is more efficient than similar devices now in use, and further may be operated at maximum speed commensurate with the ability of the operator using the device.

These and other objects and advantageous features of the invention not at this time more particularly pointed out will become more apparent as the nature of the invention is better understood from the following detailed description taken in conjunction with the accompanying drawings, wherein like reference characters denote corresponding parts, and wherein:

Figure 1 is a top plan view of a sorting machine made in accordance with the present invention with parts thereof broken away and in section;

Figure 2 is a side elevational view of the sorting machine illustrated in Figure 1;

Figure 3 is an enlarged fragmentary perspective view of the pick up mechanism of the sorting machine;

Figure 4 is a fragmentary elevational view of

2

the solenoid for controlling the actuation of the pick up mechanism taken on the line 4—4 of Figure 1;

Figure 5 is a sectional detail view taken on the line 5—5 of Figure 4;

Figure 6 is a schematic electrical circuit diagram covering the electrical circuit of the solenoid shown in Figure 4;

Figure 7 is a schematic electric circuit diagram covering the electrical circuit of the magnet employed for controlling the selector bars of the transmission mechanism;

Figure 8 is a transverse sectional view of the apparatus taken on the line 8—8 of Figure 1;

Figure 9 is a fragmentary sectional view taken on the line 9—9 of Figure 1;

Figure 10 is a sectional view taken on the line 10—10 of Figure 1 and showing the switch in the magnet circuit illustrated in Figure 7;

Figure 11 is a sectional view taken on the line 11—11 of Figure 1 and illustrating the solenoid circuit switch controlled by the keyboard of the device; and

Figures 12, 13 and 14 are enlarged diagrammatic views illustrating the pick up roll shaft and solenoid cam in successive stages of operation.

With reference to the accompanying drawings, there is illustrated a sorting machine embodying the teachings of the present invention and comprising a base frame 10, the top surface 11 of which serves as a supporting surface upon which the mechanism of the device is disposed. The forward end of the frame 10 supports the pick up mechanism of the device and is broadly indicated by the numeral 12, and the rear portion of the frame supports the transmission and stacking mechanism of the device and is indicated broadly by the numeral 13.

The pick up mechanism 12 mounted on the forward end of the frame 10 includes a box-like open top container 14 (Figure 3) adapted to receive a stack of cards "A" to be sorted, and having a pair of spaced side walls 15 and 16, formed at their rearward edge portions with in-turned vertical flanges 17 and 18 respectively.

The container is supported on foot members 19 formed on walls 15 and 16 which are preferably secured in any suitable manner to the supporting surface 11. A front wall 20 which is box-like in configuration receives the front edges of the side members 15 and 16 and completes the container for the stack of cards "A." The top flange 21 of the wall 20 is adapted to engage the forward edge portion of the top card of the

stack of cards and each successive one as the cards are picked up from the stack. Within the container 14 the stack of cards is disposed upon an elevator platform 22 (see Figure 9) having guide pins 23 depending from the lower surface thereof and slidably received within suitable openings in a supporting member 24 secured to and extending between the side frame members 15 and 16. Encircling the pins 23 and positioned between the platform 22 and support member 24 are compression springs 25 which serve to normally urge the platform upwardly so as to have the uppermost card of the stack disposed on the platform in proper position to be removed therefrom by the pick up mechanism.

The rearmost corners of the side frame members 15 and 16 are continued upwardly above the top of the container 14 and terminate in forwardly projecting ears 26. Horizontally journaled in the upward extensions of the side frames 15 and 16 and extending therebetween is a rotatable shaft 27 which is arranged to extend over the top of the stack of cards "A" disposed in the container 14. Keyed to the shaft 27 intermediate the extremities thereof is a roller 28 (Figure 12) which is suitably slotted as at 29 to receive a strip of rubber 30. The rubber strip 30 projects outwardly from the surface of the roller 28 and when the latter is rotated is adapted to frictionally engage the surface of the top card of the stack of cards "A" which is firmly pressed thereagainst by springs 25 acting on platform 22. Rotatively mounted on the shaft 27 and positioned at each end of the roller 28 are idler rollers 31, the purpose of which will be described hereinafter. The shaft 27 projects beyond the side member 15 of the container 14 and has keyed on its outer end an arm 32, the latter having pin 33 projecting from its outer end in a direction parallel with the axis of the shaft 27.

With reference to Figure 4 of the drawings there is illustrated mechanism for controlling the rotation of the shaft 27. Secured to the outer surface of the side wall 15 is a U-shaped bracket 34, the free arms 35 of which project in a horizontal position and have mounted therebetween a solenoid 36. The solenoid 36 is provided with a plunger 37, the upper end of which projects through the upper arm 35 of the bracket 34. Spaced from the upper arm 35 and secured to the plunger 37 is a plate 38 which is suitably apertured to receive the upstanding pins 39 mounted on the upper arm 35 of the bracket 34. Encircling the pins 39 and serving to urge the plunger 37 upwardly and maintain it in its extended position with respect to the solenoid 36 are compression springs 40. Mounted on the free end of the solenoid plunger 37 is a cam element 41. The surface of the element 41 facing the arm 32 is formed with spaced horizontal slots 42 and 43 projecting from opposite sides of the element and connected at their inner ends with a vertical slot 44. All of the slots are of the same width and are adapted to receive the end of pin 33. Rotation of the shaft 27 is controlled by the position of the cam element 41 mounted on plunger shaft 37.

The opposite end of shaft 27 projects beyond the side member 16 and has keyed thereon a wheel 45, the peripheral surface of which is covered with a suitable friction material 46. A spring 47 extending between a pin 48 mounted on the side frame member 16 and a pin 49 on

the wheel 45 serves to urge the wheel 45 in a counter-clockwise direction as viewed in Figure 3 of the drawings. Carried on the base member 10 is a bracket 51 which is adapted to support a motor 52. The driven shaft 53 of the motor 52 carries a wheel 54, the periphery of which is arranged to engage the periphery of the wheel 45 and drive the latter. The motor and wheel 54 are continuously rotating. Accordingly, the surface of the wheel 45 is cut away as at 55 complementary to the surface of the wheel 54 to provide an area of non-engagement between wheels 45 and 54.

As viewed in Figure 12 the shaft 27 is held against rotative movement by the position of pin 33 in the bottom of vertical slot 44 of cam element 41. When the solenoid 36 is energized the plunger carrying the cam element 41 is moved downwardly and pin 33 passes upwardly in slot 44 and into alignment with slot 42 thereby releasing pin 33 from the cam element. Release of pin 33 by the cam element 41 permits spring 47 to rotate shaft 27 beyond the area of non-engagement between the wheels 45 and 54 to the position shown in Figure 13 where wheel 54 is effective to rotate wheel 45. As roller 28 carried by shaft 27 is rotated the rubber strip carried thereby engages the top card of the stack and buckles it up as shown in Figure 13. Continued rotation snaps the flexible card to where the rearward edge portion thereof lies on the upper surface of the roller 28 as shown in Figure 14, in which position the shaft has completed one full rotation and is in the position shown in Figure 12. The solenoid upon being de-energized permits the upward movement of the cam 41 in response to pressure of the springs 40 thereby bringing slot 43 of the cam element into registry with the end of pin 33 (Figure 12) which enters the same and positions itself at the lower extremity of the vertical slot 44 in position for the succeeding cycle of operation.

Mounted on the surface 11 of the base 10 forward of the container 14 is an elongated switch box 57 formed of a suitable electrical insulating material. The box 57 is of inverted U-shape in cross section, the legs of which are cut away to form longitudinal slots 58 and 59. Mounted in the slot 58 is a conductor bar 60 which is connected through conductor 61 to one terminal of a transformer 62. The slot 59 carries a conductor bar 63 which is connected to one outlet of solenoid 36 through conductor 64. The other outlet of solenoid 36 is connected to the other terminal of transformer 62 through conductor 65. Extending through the top surface of the box 57 is a plurality of openings, each of which is adapted to receive a switch button 66, the lower surface of which is supported on the end of a spring element 67, the other end of which is connected to conductor bar 63. The spring element 67 adjacent the bottom of button 66 carries contact button 70. Extending from the conductor bar 60 is a plurality of arms 71 having contact buttons 72 mounted on their outer free ends and arranged to be engaged by contact buttons 70. When a switch button 66 is depressed, bringing contact buttons 70 and 72 into engagement, an electrical circuit is closed through the solenoid 36 as illustrated in the wiring diagram of Figure 6.

Suitably positioned on the surface 11 of the base plate 10 are a plurality of upstanding studs 73, being secured to the base plate by a threaded shank which extends therethrough and receives

a nut 74 below the plate. Each stud 73 is provided with a bifurcated end 75 receiving therein a lever arm 76. A pin 77 extending through the bifurcated end of the stud 73 and the arm 76 provides a pivotal connection for the arm 76. The lever arm 76 is provided with a key top 78 for manual operation. The lower edge surface of the arm 76 adjacent the button 78 is provided with a depending projection 79 which is adapted to engage the upper surface of button 66 for actuating the same. As shown in Figures 1 and 3 of the drawings, there are provided ten of the lever arms 76, each with a key top mounted thereon. The key tops are assigned to the ten numerical characters 0 to 9 inclusive. The number of lever arms may be increased in case assorting other than numerical is used.

Extending in straight alignment backwardly from the pick up mechanism 12 is the transmission and stacking mechanism 13, comprising a substantially rectangular frame having longitudinal side members 80 and 81 and end members 82 and 83. The frame is supported on base 10 in a horizontal alignment with the upper surface of roll 28 by means of columns 84 disposed at the four corners thereof. The opposed sides of the side members 80 and 81 of the frame are provided with aligned journals 85 which support therebetween shafts 86. Rotatably mounted on each of the shafts 86 in longitudinal alignment are idler rollers 87. Disposed between each set of rollers 87 is a transverse partition 88 which defines a plurality of stacking receptacles 89. An inclined plate 90 is disposed in the bottom of each receptacle to facilitate the alignment of the cards disposed therein.

Journalized in the ears 26 of the side members 15 and 16 of the container 14 is a shaft 91 which has rotatably mounted thereon spaced rollers 92 and 93 which are disposed in alignment with the rollers 87 carried on the shafts 86. At the rear of the transfer mechanism 13 and journaled in the frame members 80 and 81 is a shaft 94 upon which are mounted spaced rollers 95 and 96. The rollers 95 and 96 are in longitudinal alignment with the rollers 92 and 93, respectively, on shaft 91. A conveyor belt 97 is adapted to pass around the rollers 92 and 95 and a second conveyor belt 98 passes around the rollers 93 and 96. The shaft 94 is adapted to be driven by means of an electric motor 99 through a coupling 100. The motor 99 is preferably supported upon the rear portion of the supporting plate 10 by means of a suitable bracket 101.

Extending longitudinally of the transfer mechanism 13 are a plurality of stacked strip members 102 which define runways therebetween through which the cards picked up by the pick up mechanism are conveyed by belts 97 and 98 to the receptacles 89. The stacked strip members 102 are of progressively increasing length from the bottom of the stack towards the top. The forward ends of the strip members have rounded end edges which rest on plate 125 supported between end frame member 82 and cross member 82a extending between side frame members 80 and 81 and each strip defines with the next adjacent strip a runway through which a card is adapted to be conveyed. The rearward end of the strip members is supported by the top edge of partitions 88 as at 88a and is inclined downwardly to direct the card carried thereby into a receptacle 89.

Mounted below the plate 125 is a frame 110 which is adapted to house therein a plurality of

vertically movable selector bars 111. The selector bars project through apertures in the plate 125 and are provided with inclined upper surface 112, the apex of which is positioned immediately behind the forward edge of each of the members 102. There is provided one of the selector bars 111 for each of the runways defined by two adjacent members 102. Adjacent the lower end of each of the selector bars 111 there is provided an outwardly projecting pin 113 which is received within the bifurcated end portion 75 of the end of the lever arm 76, the latter being extended to engage the stud 73 upon the particular selector bar 111 which it is adapted to actuate. Upon movement of a card along the transmission mechanism in response to movement of the belts 97 and 98, the operator, by depressing one of the keys 78, projects the upper end 112 of the member 111 into the path of the card thereby deflecting it into the designated runway. Supported by a bracket 126 on frame 110 is an electromagnet 115 which extends the length of the group of selector bars 111 and is adapted to attract a projection 127 formed on the bars 111 when the same is brought into proximity to the magnet. When energized the magnet is adapted to hold one of the members 111 in its elevated position until the current to the magnet is interrupted.

Positioned immediately rearwardly of the second last runway in the path of travel of a card along the transmission mechanism is a switch 116 which takes the form illustrated in Figure 10 of the drawings. The switch 116 is supported on the longitudinal frame member 81 and has an angulated arm 117 which projects over the path of a card being moved along by the conveyor belts 97 and 98. The arm 117 is provided with a downwardly inclined spring contact member 118 which is connected to an electric conductor 119. An arm 120 extending outwardly from the member 81 carries an upwardly inclined spring contact member 121 which is connected to conductor 122. The arms 117 and 120 are preferably made of electrical insulating material and serve to support the contacts 118 and 121 in such a manner that their extremities are normally in contact so that a circuit thereacross is maintained at all times.

With reference to Figure 7 the electrical circuit for the magnet 115 is described as follows: Current flows from a transformer 123 through conductor 119 to contact element 118 of switch 116, thence to contact element 121 through line 122 to one terminal of magnet 115, thence from the other terminal of magnet 115 through conductor 124 to the other terminal of transformer 123. The circuit to the magnet is normally closed, energizing the magnet at all times. Upon depressing one of the keys 78 the lever arm 76 actuated thereby is pivoted about its stud 73 raising a member 111 which is held in its elevated position by the magnet 115. A card moving along the conveyor is adapted to pass between contacts 118 and 121 opening the circuit to the magnet 115 which permits the member 111 previously elevated by lever 76 to drop to its normal position.

In using the device of the present invention for numerical assorting, a stack of unassorted cards, number side up, is placed upon the platform 22 in the container 14, the forward edges thereof being projected under the flange 21 of the front plate 20. To effect this the spring 23 are depressed to permit the stacking of the cards

"A." The motor 99 is started thereby setting in motion the belts 97 and 98 which as viewed in Figures 1 and 2 move in a clockwise direction. The motor 51 is started thereby setting in operation the driving wheel 54 which as viewed in Figures 12, 13 and 14 is moving also in a clockwise direction.

Assuming that the number on the topmost card is 1145, the operator depresses the key bearing the numerical designation "5," note Figures 1 and 3. The single downward stroke of this key closes the circuit to the solenoid 36, the current flowing from the transformer 62 through conductor 61, thence across the contacts 71 and 72 through conductor 64 to solenoid 36 and thence through conductor 65 to the other terminal of transformer 62 to complete the circuit. Energization of the solenoid 36 retracts plunger 37 moving cam element 41 downwardly to release the pin 33. In response to pressure of spring 47 the periphery of wheel 45 is brought into engagement with the continuously rotating wheel 54 and the former is caused to make one complete revolution rotating shaft 27 and the roller 28 carried thereby.

Immediately following the start of the turn of roller 28 the friction surface of the element 30 carried thereby comes in contact with the surface of the top card, causing it to buckle and the rearward edge thereof to move beyond the outer surface of roll 28. At this point the edge of the card snaps upwardly and lays upon the roll 28 as shown in Figure 14. In this position, since the pressure exerted on the leading edge of the top card between moving belts 97 and 98 and rollers 31 is greater than that exerted on the trailing edge of said card between the flange 21 and the supporting stack of cards, now projected under the moving belts 97 and 98, is gripped between the same and rollers 31 and by the same force conveyed by said belt over the top surfaces of rollers 87. Depressing the key "5" pivots the lever 76 associated therewith about its pivot pin 77 moving the selector bar 111 connected to the outer end thereof vertically to bring the inclined surface 112 thereof into the path of the moving card. The card with its top surface adjacent to the frictionized belts and its bottom surface supported by the smooth plate 125 is moved by the belts along the conveyor with its central portion deflected upwardly into the runway leading to the receptacle controlled by the number "5" key. The card when it has entered the runway is urged rearwardly by the belts making frictional contact with the right and left top surface of said card with intermittent support on the bottom surface by the spaced idler rollers 87. The magnet 115 maintains the selector bar 111 in its elevated position upon release of the key 78, until the card passes between the contact elements 118 and 121 of switch 116 breaking the circuit to the magnet 115 and permitting the selector bar 111 to return to its normal position. Immediately upon passage of the card past the switch 116 the circuit to the magnet 115 is closed.

Each card in container 14 is picked up, conveyed to and deposited in its respective receiving receptacle 89, in a similar manner as that described above by depressing the key bearing the numerical designation of the units digit of the number appearing on the respective card.

When the stack of cards originally placed in the container 14 is disposed of as above described and this does not constitute the entire group of cards to be sorted, another stack of unassorted

cards is placed in container 14 and likewise assorted to the units digits of the numbers appearing on the respective cards. This procedure is repeated as necessary until all of the cards to be assorted have been disposed of and then the cards are removed from the respective receptacles and stacked numbered side up, in numerical order in respect to the units digits. The entire re-assembled group of cards is again processed through the machine, the same procedure as that described above being repeated with respect to the next digit of the numbers, for example the "10" digit of the numbers, and this complete operation is repeated until an assortment of all of the numbers has been made with respect to all of the digits controlling the numbers thereon. Upon completion of this assortment, the stacking of the tickets will arrange them in numerical sequence.

Having thus described my invention, what I desire to obtain by Letters Patent is defined in the appended claims.

I claim:

1. A card sorting machine comprising a conveyor extending longitudinally of the machine, means for moving cards along said conveyor, a plurality of receptacles adapted to receive cards from said conveyor, a plurality of runways positioned above said conveyor and starting forwardly of said receptacles adapted to guide cards moving along said conveyor into said receptacles, vertically movable selector bars positioned adjacent the forward terminus of said runways and arranged to intercept the travel of the cards along said conveyor and direct the same into one of said runways, manually actuated means for moving separate selector bars into the path of the moving cards, magnetic means for maintaining said selector bars in their elevated position, pick up means for moving the top card from a stack disposed at one end of the conveyor onto said conveyor, and electrically controlled means for actuating said pick up means.

2. A card sorting machine comprising a conveyor extending longitudinally of the machine, a plurality of belts for moving cards along said conveyor, a plurality of horizontally arranged receptacles positioned below the conveyor and adapted to receive cards, a plurality of runways positioned above said conveyor starting forwardly of said receptacles serving to guide cards moving along said conveyor into said receptacles, vertically movable selector bars positioned adjacent the forward terminus of said runways and arranged to intercept the travel of the cards along said conveyor and direct the same into said runways, manually actuated means for moving separate selector bars into the path of the moving cards, magnetic means for maintaining said selector bars in their elevated position, means responsive to the movement of a card for releasing said selector bars and permitting the return thereof to normal position, pick up means for moving the top card from a stack disposed at one end of the conveyor onto said conveyor, and electrically controlled means for actuating said pick up means.

3. A card sorting machine comprising a conveyor extending longitudinally of the machine, means for moving cards along said conveyor, a plurality of receptacles arranged horizontally below said conveyor adapted to receive cards being sorted, a plurality of runways superimposed one above the other starting forwardly of said receptacles for guiding cards moving along said con-

veyor into said receptacles, vertically movable selector bars positioned adjacent the forward terminus of said runways and arranged to intercept the travel of the cards along said conveyor and direct the same into said runways, manually actuated means for moving separate selector bars into the path of the moving cards, magnetic means for maintaining said selector bars in their elevated position, a container positioned at the forward end of said conveyor adapted to receive a stack of cards to be sorted, pick up means for moving the top card from the stack disposed in said container onto said conveyor, and electrical- 10 ly controlled means for actuating said pick up means.

4. A card sorting machine comprising a conveyor extending longitudinally of the machine, means for moving cards along said conveyor, a plurality of receptacles horizontally arranged below the conveyor for receiving said cards, a plurality of runways positioned above said conveyor starting forwardly of said receptacle and adapted to guide cards moving along said conveyor into designated receptacles, vertically movable selector bars positioned adjacent the forward terminus of said runways and arranged to intercept the travel of the cards along said conveyor and direct the same into said runways, pick up means for moving the top card from a stack disposed forwardly of the conveyor onto said conveyor, electrically controlled means for actuating said pick up means, and a plurality of manually actuated keys for simultaneously controlling the actuation of said selector bars and pick up means.

5. A card sorting machine comprising a conveyor extending longitudinally of the machine, means for moving cards along said conveyor, a plurality of receptacles adapted to receive cards from said conveyor, a plurality of runways positioned above said conveyor starting forwardly of said receptacles and terminating selectively at the entrance to said receptacles, selector bars positioned adjacent the forward terminus of said runways and arranged to intercept the travel of the cards along said conveyor and direct the same into said runways, manually actuated means for moving separate selector bars into the path of the moving cards, a container positioned at the forward end of said conveyor adapted to receive a stack of cards to be sorted, pick up means for moving the top card from the stack and delivering same to said conveyor, said pick up means including a roller engageable with the top card of the stack, means for rotating the roller through a complete revolution, solenoid actuated cam means for controlling the rotation of said roller, and key members for controlling the solenoid circuit and the movement of said selector bars.

6. A card sorting machine comprising a conveyor extending longitudinally of the machine, means for moving cards along said conveyor, a plurality of receptacles adapted to receive cards from said conveyor, a plurality of runways positioned above said conveyor starting forwardly of said receptacles and adapted to guide cards

5 moving along said conveyor into said receptacles, vertically movable selector bars positioned adjacent the forward terminus of said runways and arranged to intercept the travel of the cards along said conveyor and direct the same into said runways, pick up means for moving the top card from a stack disposed forwardly of the conveyor onto said conveyor, said pick up means including a rotatable shaft carrying card engaging means, a cam member for controlling the rotation of said shaft, a solenoid for moving said cam means into and out of engagement with said shaft, and manually actuated means for simultaneously moving separate selector bars and closing the circuit to said solenoid.

10 7. A card sorting machine comprising a conveyor for moving cards longitudinally of the machine, a plurality of card receptacles arranged horizontally below said conveyor, a plurality of runways superimposed one upon another above said conveyor having the forward end thereof starting forwardly of the receptacles and terminating selectively above said receptacles for guiding cards moving along said conveyor into said receptacles, vertically movable selector bars positioned adjacent the forward terminus of said runways and arranged to intercept the travel of the cards along said conveyor and direct the same into said runways, magnetic means for maintaining said selector bars in their elevated card intercepting position, and means responsive to the movement of a card along said conveyor for interrupting the flow of current to said magnetic means and thereby releasing said selector bars.

20 30 40 50 55 8. A card sorting machine comprising a conveyor for moving cards longitudinally of the machine, a plurality of card receptacles arranged below said conveyor, a plurality of runways for guiding cards moving along said conveyor into said receptacles having the forward end thereof positioned forwardly of the receptacles and terminating selectively above said receptacles, vertically movable selector bars positioned adjacent the forward terminus of said runways and arranged to intercept the travel of the cards along said conveyor and direct the same into said runways, manually actuated means for moving separate selector bars into the path of the moving cards, magnetic means for maintaining said selector bars in their elevated position, and means responsive to the movement of a card along said conveyor for interrupting the flow of current to said magnetic means and thereby releasing said selector bars.

BLAKE L. MISHEY.
